STEREOTYPE PLATE FINISHING
MACHINEGeorge E. Pancoast, Seabright, N. J., assignor to
Wood Newspaper Machinery Corporation, New
York, N. Y., a corporation of Virginia

Application August 16, 1933, Serial No. 685,404

6 Claims. (Cl. 29—21)

This invention relates to that type of machine used in finishing stereotype printing plates and particularly plates used in newspaper printing. It also relates specifically to that type of finishing machine in which two or more machines deliver the plates to one conveyor or other destination.

The principal object of this invention is to provide an efficient and simple means for so timing the discharge of plates from each one of the finishing machines of a set served by a single conveyor or the like that the plates from one conveyor will be forced to alternate with those of any other without interference with each other as they come into the conveyor.

Another object of the invention is to provide means whereby, in case the machines are not set properly, the motor which operates the two or more finishing machines will be caused to stop.

Other objects and advantages of the invention will appear hereinafter.

Reference is to be had to the accompanying drawings, in which

Fig. 1 is a plan of a set of two finishing machines or "autoshavers" driven by a single motor, both of which discharge plates to a common conveyor;

Fig. 2 is an elevation of the same;

Fig. 2a is a continuation thereof;

Fig. 3 is a sectional view on the line 3—3 of Fig. 1;

Fig. 4 is an end view of one of the "autoshavers" showing the switch cam;

Fig. 5 is an end view of the other "autoshaver" and these two figures show the proper relative positions of the two switch cams; and

Fig. 6 is a diagrammatic view showing the two switch cams out of time and demonstrating how the switches in the control circuit of the motor cause it to cease operating.

In a multiple machine of this kind an individual shaving machine performs the function of shaving the inside of the plate, cooling the plate and wiping excess water from the inside of the plate, as usual. After this, it is delivered to the conveyor. These multiple machines are used in moderate sized printing plants.

It has been the practice heretofore to supply an intricate system of switches so that one plate coming from one finishing machine will not foul that coming from another. By this invention the machines are absolutely stopped at the beginning of an operation which would cause the plates to come into contact with each other.

An "autoshaver" 1 is shown having a loading

platform 2 on which a plate P may be placed, as usual. The usual plate stops 3, 4 and 5 serve to time the release of the plate from each of the positions so that the machine may function properly. Two "autoshavers" are shown and each is provided with these features and with an arch 6 mounted on the side frames for the usual purpose.

The usual knives 7 are provided and the shaving knife bars 8 are rotatably mounted concentric with the arch, on each of which is a worm wheel 9 through which it receives its drive from a worm 10 which may be considered as integral with a shaft 11. The latter is mounted by bearings in the frame of the machine and carries a shear pin hub 12 which, by means of a shear pin 13, is connected with a shear pin hub 14 carried on a transverse shaft 15. On the other end of the shaft 15 is fixed a bevel gear 16.

The shaft 15 is rotatably mounted in bearings 75 on a motor frame 17 which provides a support for the operating motor 18 and the bearing for the end of the motor shaft 19 which is coupled to the motor by a coupling 20. Secured to the shaft 19 is a bevel pinion 21 which meshes with two bevel gears 16 on the opposite sides, in the form shown.

As will appear from the above, each of the bevel gears 16 operates one of the "autoshavers". The rotation of the armature of the motor 18, 85 through the shaft 19 and pinion 21, drives the two shaving machines.

On the upper end of the knife bar 8 of each of the two inclined machines is fixed a switch cam 22. If a battery of two machines is running, each switch cam has a high portion of 180° substantially and a low portion of the same arc. Each of these cams operates the roller of an electric switch 23 in one case and 24 in the other.

It will be apparent that, by removing the shear pins 13 of either one of the shear pin couplings, one "autoshaver" may be rotated independently of the other so that the knife bars may take any particular angular relation to each other, 100 as shown in Fig. 3, which is the proper position. Then by replacing the shear pins, both "autoshavers" will be driven at once and contact will be established in the switch 23 before a contact is broken in switch 24 and vice versa. 105 These switches are in parallel circuits, as shown in Fig. 6, which parallel circuits are in circuit with the motor circuit. Therefore, if the two cams both get on the low part at the same time the motor circuit will be broken and both ma- 110

chines will stop. This is what is shown in Fig. 6. It will be seen therefore that the two switches 23 and 24 are used to insure proper timing for the two shaving machines to obtain the desired sequence in the discharge of the plates therefrom and if that sequence is not correct or nearly correct the machine will not operate.

In Fig. 1 a plate P' is shown, being delivered to a conveyor 25 from the "autoshaver" A while 10 a plate P is just being discharged from the "autoshaver" B. The timing is such that the conveyor will have moved the plate P' out of the chute 27 by the time the plate P reaches the conveyor.

15 It is evident that there is some leeway and that it is not absolutely necessary that the "autoshavers" be spaced 180° and that when the run from one "autoshaver" is different from that of its companion "autoshaver" it will be desirable 20 to set the shaving knives at some angular displacement other than 180° to obtain proper timing of the plates delivered to the conveyor 25. This can be done by properly adjusting the switch cams 22.

25 Of course, in cases where three or more "autoshavers" are arranged to deliver to a single conveyor the relationship will be different in obvious particulars.

It will be seen that in a plant of this type the 30 difficulties heretofore mentioned are avoided in a very simple manner which works mechanically and without any delicate timing devices or any intricate system of switch trips or the like.

Although I have illustrated and described only 35 one form of the invention I am aware of the fact that modifications can be made therein by any person skilled in the art without departing from the scope of the invention as expressed in the claims. Therefore, I do not wish to be limited in this respect otherwise than as set forth in the claims, but what I claim is:—

1. In a plant for preparing stereotype printing plates, the combination of a plurality of finishing machines, a single conveyor, and means by which 45 the plates can be delivered from the finishing machines to the conveyor, with means for timing the discharge of the plates from the several finishing machines so that the plates will reach the conveyor in proper sequence without interference with each other.

2. In a plant for finishing castings, the combination with a plurality of finishing machines, a conveyor for receiving the products, and means 55 for transferring the products from all of said machines to said conveyor, of means for operating all of said finishing machines and means whereby, when any of said machines is so timed as to so operate with respect to the other machine or machines that the products would inter-

60

fere with each other in passing to the conveyor, all the machines will stop.

3. In a plant for finishing stereotype printing plates, the combination of a plurality of finishing machines, a single device to which said machines deliver their finished product, a single means for operating the finishing machines, and means whereby, when a machine is so timed with respect to another that it will deliver its product at a time to engage the product of another machine, the said machine will be stopped automatically.

4. The combination of a plurality of finishing machines, a motor, means for connecting the motor with both machines for operating them, a conveyor arranged in position to receive the products from said machines, and means whereby said machines can be turned independently of each other for the purpose of adjusting the relationship of the delivery of the products therefrom so that they will not interfere with each other in passing to the conveyor.

5. The combination with a plurality of finishing machines, a motor having a pinion operated thereby, a plurality of gears meshing with said pinions, a shaft connected with each gear, means operated by said shafts for operating the finishing machines, each finishing machine having a shaft, a cam on each of the last named shafts, and a switch for each cam, said switches being arranged to be held closed when the high part of their respective cams pass through a certain arc, and all the cams together being so arranged that one or the other of said switches will be closed at all times during the normal operation of the machine.

6. The combination with a plurality of finishing machines, a motor having a pinion operated thereby, a plurality of gears meshing with said pinion, a shaft connected with each gear, means operated by said shafts for operating the finishing machines, each finishing machine having a shaft, a cam on each of the last named shafts, a switch for each cam, said switches being arranged to be held closed when the high part of their respective cams pass through a certain arc, and all the cams together being so arranged that one or the other of said switches will be closed at all times during the normal operation of the machine, parallel circuits in which said switches are located, and a main circuit connected with the parallel circuits and the motor, whereby if one of said cams is sufficiently out of position, all the branch circuits will be opened at the same instant during the rotation of the shafts and the motor will stop, thus stopping the machine.
